COOLING SYSTEM FOR CONTINUOUS
CASTING MOLDS

Irving Rossi, Morristown, N. J., assignor to Continuous Metaleast Corporation, Wilmington, Del., a corporation of Delaware

Application September 30, 1947, Serial No. 776,936

1 Claim. (Cl. 22—57.2)

1

My present invention relates to continuous casting systems and more particularly to a cooling method and system for a continuous casting metal mold so designed that the water circulation around the mold is horizontal rather than vertical. In fact, my invention is directed to a structure and method wherein the water circulation around the mold is in the form of a horizontal sheet of water guided around the mold by appropriate guides and caused to circulate properly into contact with the mold by appropriate baffles, the said substantially horizontal sheet of water being a fast moving large volume sheet with no vertical component of motion.

Heretofore in the casting of ingots and billets, as well as in continuous casting operations, the cooling system for the mold where water was used as the cooling fluid was one in which the water was generally introduced at the top of the mold and caused to flow or circulate downwardly to the bottom of the mold where it was discharged.

Some prior systems simply permitted the water to flow downwardly in the cooling jacket while others utilized arrangements of baffles or even spiral tube arrangements which gave the water flow some horizontal component although its essential direction was vertical from the top to the bottom of the mold.

In other cooling systems, water was introduced at the bottom of the mold jacket, and in some systems water was introduced at the center of the mold jacket and permitted to gravitate downwardly and then to rise upwardly in order to provide a cooling operation.

In continuous casting systems, metal is poured into a mold, the metal usually being led, down in a spout which enters below the top level of the liquid in the mold, thus obviating splashing which would otherwise cause turbulence in the liquid and resultant porosity in the casting.

The bottom of the mold is open. It thus becomes necessary to freeze at least the outer shell of the metal very rapidly so that the frozen shell within the mold will itself form a mold.

Consequently, it is usually desirable to have the outer shell of the metal cast in the continuous casting mold frozen before it has moved down more than an inch or two from the top level of the metal in the mold.

When the outer metal shell thus solidifies, it shrinks away from the mold, solidifying gradually inwardly toward the center of the billet being cast and forming a crater which holds the molten metal in the mold. The sides of this crater are

2

continuously freezing toward each other, but the crater is continuously reformed as the metal moves down the mold.

In contrast with ordinary casting processes, it is desirable in a continuous casting process to maintain uniform freezing throughout the entire solidification process and, therefore, to obtain uniform heat transfer along the entire height of the mold.

At the bottom of the mold, the molten metal at the center of the apex must be cooled by conduction through the entire frozen transverse weight of metal already solidified; while at the top of the mold, the outer shell of the billet in contact with the mold wall should be frozen almost instantaneously.

The shell should be maintained in frozen condition throughout the entire height of the mold as it passes therethrough, since any rise in temperature of the shell may cause it to remelt. The remelting of the metal of the billet may permit leaking through of eutectics of the alloy with a lower melting point than the main alloy to produce exudations or beads of molten metal on the surface of the billet. These eutectics of the main alloy appear to pierce the shell in small beads and as they flow through these apertures, they carry with them a volume of heat which in turn remelts the perimeter of the small

opening causing it to enlarge and to permit further exudation or bleeding. If the opening becomes too large then the entire liquid center of the billet may flow out and cause the complete disintegration of the shell at that particular point.

Consequently, it is desirable and, in fact, essential to proper uniform continuous casting operations to cool the entire mold instantaneously to the lowest possible temperature.

If any variation in the cooling operation at different heights in the mold wall is to be had, the cooling at the bottom of the mold should be even greater than at the top; but the basic principle of freezing the outer shell of the billet first and then progressively freezing the inner portion of the billet as rapidly as possible makes it unnecessary to have any critical differences in temperature at different levels of the mold but rather requires that the whole mold wall be simultaneously chilled and maintained in chilled condition at the lowest possible temperature.

This is in contra-distinction to single or non-continuous casting operations where it is necessary, in order to prevent porosity, cold shuts and

cracks, to maintain an elevated temperature at the bottom of the mold and, therefore, a correspondingly elevated temperature through the height of the mold.

The primary object of my invention is thus the provision of cooling means particularly adapted to a mold for a continuous metal casting operation wherein the cooling fluid, preferably water, is circulated horizontally in the form of a fast flowing horizontal sheet around the mold.

Another object of my invention is the provision of novel simplified flow control and baffle means to provide an appropriate flow of horizontally directed cooling fluid, the guiding means being also arranged to direct the cooling fluid against the side of the mold in order to obtain appropriate heat circulation.

Heretofore in the utilization of cooling means and jackets in which the flow of water was essentially vertical, the uniformity of cooling around the entire vertical distance of the mold as well as around the entire perimeter of the mold was difficult and in fact almost impossible.

Another and important object of my invention therefore is the production of uniform cooling around the entire vertical distance of the mold and around the entire perimeter of the mold by utilization of a fast flowing horizontally moving sheet of water around the mold, the rate of water flow being so rapid that there will be very little rise in temperature, if any, as the water flows around the entire perimeter of the billet.

In order to accomplish the foregoing, my invention contemplates the utilization of a water intake chamber adjacent the cooling jacket, the said water intake chamber being equal in height to the full height of the cooling jacket. The cooling water is received under appropriate pressure in the water intake chamber; a vertical slot the full height of the cooling jacket forms a communicating path between the water intake chamber and the water jacket. The water under pressure enters the vertical slot and moves as a sheet of water in a horizontal direction around the mold exiting through a similar vertical slot into a water outlet chamber which is placed alongside the water intake chamber.

Owing to the rapid rate of flow of the sheet of water in a horizontal direction around the mold, its temperature is raised very little and the exhaust water taken from the water outlet chamber may be utilized for further cooling purposes and thus may, if desired, be directed to a cooling jacket or boot surrounding the portion of the billet which exits from the mold.

Appropriate preferably vertical baffles are provided in the cooling jacket, being so arranged as to cause turbulence in the sheet of water moving rapidly around the mold thereby directing the water against the side of the mold and increasing the heat exchange between the water and the mold.

Thus, another object of my invention is the provision of vertical water intake and outlet chambers alongside each other at one side of the mold with means for causing the water to enter from the water intake chamber into the cooling jacket in the initial form of a sheet of water the full height of the mold, the water moving around the mold and exiting to the water outlet chamber whence it is withdrawn.

In order to provide a uniform cooling operation over the vertical height of the mold, another object of my invention is the provision of a tapered

slot between the water intake chamber and the cooling jacket.

My invention is primarily intended for use in connection with the continuous casting, or semi-continuous casting, operations in which the length of the casting is greater than the length of the mold and the object to be achieved is the more rapid rate of heat removal commensurate with the alloy being cast, in order to obtain the highest possible casting rate.

In the case of individual castings, the problem of appropriate cooling operations is readily resolved since an individual casting brings into the mold a given quantity of heat which need be removed only once, whereas continuous casting renews the heat in the mold at a constant uniform rate.

In the case of individual casting, it is inadvisable to remove heat too rapidly from the metal first falling into the mold, otherwise, the metal flowing thereafter to fill up the mold will not properly weld or merge with the metal already in the mold; and if this welding does not occur, the resulting casting is imperfect in that it has cold shuts, internal cracks or porosity. Because of this, the rate of cooling of metal in such individual casting molds must be much slower than in the case with continuous casting.

For this reason, efforts are made in the case of individual castings to control the temperature of the water both as to degree and the rate of rise during its progress through the mold.

It is evident that the longer the traverse in the mold the greater will be the heat absorbed by the water in its travel through the mold.

In continuous casting processes, however, it is desirable to achieve exactly the opposite results, that is, to cool with a maximum intensity. It is important to have the water in contact with the mold for as short a period of time as possible in order to intensify the cooling effect.

It thus becomes a primary object of my invention to cause the water to circulate horizontally around the copper liner of the continuous casting mold rather than vertically. With this horizontal circulation of a vertical sheet, then postulating a mold 12" high with an inner liner 12" in diameter and a cooling jacket 1" thick, the water has only to cover a cross-section 12" x 1".

If the same volume of water were to pass vertically over the face of the mold, then it would be required to fill a cross-section 12" x 1" or more than three times the area which means that its rate of flow would be correspondingly reduced. As the rate of heat absorption is directly proportionate to the rate of water flow, then it follows that by my invention it is possible to obtain the same cooling effect with one-third less water, always providing that the rate and volume of water flow remain within the limits of common practice.

By the means provided by my invention, therefore, the maximum heat exchange is provided and maximum efficiency of a continuous casting operation is ensured.

A further object of my invention is the application of my basic principle of horizontal rapid flow water cooling to continuous casting molds of various shapes as well as to multiple billet continuous casting molds.

The foregoing and many other objects of my invention will all become apparent in the following description and drawings in which:

Figure 1 is a view in perspective of a continuous casting mold with parts thereof broken away to

illustrate the operation of my novel cooling system and method.

Figure 2 is an elevation partly in section on line 2—2 of Fig. 4 of a continuous casting mold embodying my novel cooling system showing primarily the utilization of the tapered slot in order to obtain uniform water flow.

Figure 3 is a section on line 3—3 of Fig. 4 taken at 90° from the view of Figure 2 showing the application of my novel cooling system to continuous casting mold.

Figure 4 is a top plan view of a continuous casting mold embodying my novel cooling system.

Figure 5 is a fragmentary view in perspective showing the baffles utilized in my novel cooling system.

Figure 6 is a fragmentary cross-sectional view taken on line 6—6 of Figure 5 looking in the direction of the arrows showing the relationship between the baffles of my novel cooling system and the remainder of the cooling jacket.

Figure 7 is a fragmentary view in perspective corresponding to the lower portion of Figure 1, showing the water inlet for the cooling boot below the continuous casting mold.

Figure 8 is a fragmentary view in perspective corresponding approximately to the center portion of Figure 1 showing the cooling water outlet for the cooling boot below the continuous casting mold.

Figure 9 is a horizontal cross-section through an adjustable dual slab mold showing a cooling system adapted for rectangular slabs made by a continuous casting process.

Figure 10 is a horizontal cross-section through a multiple billet mold for a continuous casting process utilizing the principles of my invention.

Referring first to Figures 1 to 4, the continuous casting mold is essentially a copper liner 10 supported in the opening 11 of the base 12. A water jacket 13 spaced approximately 1" from the copper liner 10 surrounds the copper liner 10 defining a vertical channel 14 around the copper liner or mold 10. The vertical channel 14 is substantially equal in height to the mold and is preferably of the order of 1" wide.

A plurality of vertical baffles 15 are provided on the inner surface of the jacket 13, the said baffles extending inwardly somewhat less than half the width of the channel 14 or approximately $\frac{3}{8}$ " in the case of a channel 1" in width. The baffles are tapered as seen in Figures 5 and 6 so that they are narrower at their lower end increasing the rate of flow and volume of water at the lower end of the chamber for purposes above described. The cross-sectional width of the channel 14 should be such as to permit a large volume of water to flow at a high rate therethrough around the copper liner forming the mold 10.

Thus, where appropriate water pressure is obtainable the channel 14 may be wider than 1"; but in a mold 10 the order of 12" in diameter, it is preferred that the channel 14 should not be narrower than an inch in horizontal section.

The water intake chamber 20 and the water outlet chamber 21 are defined by the outer water box 22 mounted on the support 38, the said box having the cover 23 and the interior vertical partition 24 separating the two chambers from each other. The partition 24 extends inwardly past the vertical slots 25 and 26 in the water jacket 12 almost up to the copper liner 10 forming the mold, thereby dividing the water inlet and outlet portions of the cooling channel 14 from each

other as well as dividing the water intake and outlet chambers from each other. The gap 24a (Figures 2 and 5) is provided between the end of partition 24 and the outer surface of mold wall 10 to ensure that cooling water will be directed to the portion of mold wall 10 adjacent the partition 24. This avoids a dead spot on the mold wall and ensures uniform cooling. The gap 24a is very narrow (of the order of $\frac{1}{8}$ " or less) and thus does not interfere with the water flow herein described.

Also, baffles 15a and 15b on opposite sides of the partition are inclined toward the partition to ensure that the water splashes against and cools the partition and into the gap 24a. The water pressure is such that leakage through gap 24a is negligible while at the same time, the existence of gap 24a avoids a dead spot which would otherwise cause evaporation of zinc in a bronze casting.

The water pressure is preferably such that the entire volume of water passes through the chamber 14 in two seconds or less so that the temperature rise in the water is of the order of only 25° or less.

The slots 25 and 26 are preferably tapered as shown in Figures 1 and 2 in order to ensure uniform water flow through the cooling channel 14 at every level thereof. The wider portions of the slots at the bottom ensure increased water flow 30 at the lower part of the mold.

The upper end of the cooling jacket 13 is provided with an annular flange 30 against which the water sealing gasket 31 may be compressed by the annular ring 32 which is interconnected with the annular flange 30 by bolts 33.

The gasket 31 is carried in the recess 35 of flange 30 so that when compressed it is forced against the side of the mold 10 to complete the water seal. The flange 30 may be extended to form the cover 23 of the water intake and outlet chambers 20 and 21.

The water jacket 13 is secured in any suitable manner as by welding to the horizontal support member 38 which in turn is secured in any suitable manner to the base 12. The right-hand side of the support member 38 (with respect to Figure 3) is extended to form the bottom of the water intake and outlet chambers 20 and 21.

The support 38 is compressed in any suitable manner against the annular gasket 40 held in the annular retainer 41 mounted on the water outlet ring 42 for the cooling boot 43 below the mold 10.

The water outlet ring 42 and the cooling boot 43 have no relation to my novel horizontal cooling system and method which constitutes the essence of the present invention but are included, as hereinafter more specifically described, in order to show a complete device and the relation of my novel cooling method to other elements of a complete system.

The two gaskets 31 and 40 thus serve to confine the cooling water in the cooling chamber 14 defined by water jacket 13 and mold 10. Appropriate reinforcing elements 44 may be provided between the cooling jacket 13 and the flange 30 and similar elements 45 may be provided between the cooling jacket 13 and the horizontal base 38 thereof.

As previously pointed out, my invention is specifically directed to a continuous casting system wherein the copper liner forming the mold 10 receives a continuous flow of metal from an appropriate holding or storing furnace, the metal being

frozen in its passage through the mold to emerge from the bottom thereof as a continuous billet or casting.

It thus becomes important to obtain high speed heat exchange between the metal within the mold 10 and the cooling fluid in the channel 14 defined by the water jacket 13 around the mold 10. For this purpose, water is forced at high pressure through intake pipe 50 into the water intake chamber 20. The water in the water intake chamber 20 then is forced through the tapered slot 25 in a counterclockwise direction with respect to Figure 4 around the mold 10 in the cooling chamber 14, being prevented from flowing in a clockwise direction by the partition 24 which extends almost up to the mold 10, being separated therefrom only by the small gap 24a.

When the water completes its counterclockwise circuit including chamber 14, it exits through the tapered slot 26 into the water outlet chamber 21, being prevented again from recirculating through the chamber 14 by the partition 24.

The water which has thus cooled the mold 10 now exhausts through the exhaust pipe 52; and may, since it has not been heated very much, be used for other cooling purposes such as cooling the casting A below the mold 10 in the boot 43 as hereinafter described.

The baffles 15 ensure sufficient turbulence in the horizontally moving sheet of water to bring every part of the water into contact with the mold 10 in order to provide an efficient heat exchange. The water is forced through at high speed so that the cooling fluid is continuously replaced at its original cooling temperature by new volumes of water, and so that the temperature of the water does not rise appreciably in its counterclockwise travel around the mold with respect to Figure 4. This ensures uniformity of cooling throughout the entire perimeter of the mold while the utilization of a continuous sheet of water entering simultaneously at all vertical points on the mold ensures uniform cooling for the full height of the mold.

While the exit slot 26 need not necessarily be tapered, the exit slot 26 is preferably tapered in the same manner as the entrance slot 25.

The arrangement of the baffles 15 and their spacing with respect to the mold wall 10 and water jacket 13 is more clearly indicated in Figures 5 and 6 wherein the relative depth of the baffle 15 with respect to the water chamber 14 as above described is more clearly shown.

Thus, it will be seen from the foregoing that this simplified structure permits the primary object of my invention to be achieved; that is, the water enters the vertical circular channel or chamber 14 through the vertical tapered slot 25, moves horizontally around the mold 10 and exits through slot 26. Since the temperature is not appreciably raised, no danger of warping of the partition 24 is incurred by reason of extreme differences in temperature on opposite sides of partition 24.

In fact, the exhaust water is sufficiently cool so that it may be used as the cooling fluid in the boot 43. The boot 43 surrounds the portion of the billet A below the mold 10. The billet A as it emerges from the mold 10 is, of course, in frozen or solidified form and requires no further support.

The boot is supported in any suitable manner as for instance by being suspended from the basic support 12, the diameter of the boot 43 being substantially larger than the diameter of the billet A 75

in order to provide the cooling chamber 60 between the boot 43 and the billet A.

The upper end of the water chamber 60 is sealed by annular gasket 40 above described. 5 The lower end of the boot 43 is supported in any suitable manner as by the annular flange supporting structure 63 which carries the annular water intake ring 64.

The annular water intake ring 64 has a lower 10 flange 65 which extends close to but not in contact with the billet A. A flexible gasket 66 is compressed between the annular flange 65 and the securing ring 67, said gasket 66 having a smaller internal diameter than the billet A so that the 15 billet A forces its way past the gasket 66 as shown in Figures 1, 3, and 7.

The gasket 66 thus provides the lower seal for the water chamber 60.

The boot 43 clears the bottom flange 65 of the 20 annular water intake ring 64 to provide the annular gap 70 through which water may pass from the annular intake ring into the chamber 60. The exhaust water from the outlet chamber 21 of the mold cooling apparatus is connected to the annular intake ring 64 for the chamber 60 defined by the boot 43.

Water enters the annular intake ring 64 and passes through the gap 70 up into the cooling 30 chamber 60. The water is heated by the heat exchange which then occurs and rises up to the plurality of openings 72 (Figures 1, 3 and 8) in the boot 43, which openings communicate with the annular water outlet ring 42 carried by the 35 boot 43. The water thus used for heat exchange in the lower chamber 60 defined by the boot 43 then exhausts through exhaust outlet 75.

The efficiency of my novel cooling system and method is thus emphasized by the fact that the 40 exhaust water from the mold cooling chamber may still be used efficiently to cool the billet in the boot 43 below the mold 10.

In Figures 9 and 10, I have shown the adaptation of my invention utilizing the principles of uniform horizontal flow of a volume of water 45 at a rapid rate in continuous casting molds which are not necessarily of circular or approximately circular cross-section.

In Figure 9 I have shown a cross-section through a continuous casting mold adapted to 50 form a plurality of slabs, the said mold being adjustable for different widths of slabs.

The vertical cooling plates 100, 101 each have an inner copper wall 102, 102 adapted to form the sides of the mold and an outer wall 103 which need not necessarily be of copper but which may be of steel. Each of the plates 100, 55 101 has a vertical water inlet tube 105 and an opposite vertical water outlet tube 106.

The water inlet tube 105 in each plate is connected to the interior chamber 108 in each plate 60 by the narrow vertical slot 110. Water forced under pressure into tubes 105 exits therefrom through slots 110 into the chambers 108. The water flows horizontally across the vertical chambers 108 into the vertical exit slots 112 into the 65 exhaust tubes 106.

Appropriate baffles may be provided, if desired, in chambers 108 to ensure sufficient turbulence. The vertical slots 110, 110 may be tapered, as previously described in connection with the slots of the structures of Figures 1 to 6, in order to ensure uniform flow of water or even an increased flow of water at the bottom.

The actual individual molds 115, 116 are formed by the copper walls 120, 120 and the

graphite separators 117, 118, 119. The plates 100, 101 are clamped together on opposite sides of the vertical graphite separators 117, 118, and 119 in any suitable manner as by bolts 120 tightened through openings in lugs 121, 121 extending from the ends of plates 100 and 101.

In this case, the cooling occurs only at the sides of the slabs in molds 115 and 116. This cooling operation is, however, sufficient in the case of rectangular slabs of this type, first, because the slabs are relatively very narrow and the chilled portions of the slabs on opposite sides will crystallize toward each other very rapidly and second because cooling at the ends of each slab would result in greater shrinkage at the ends of the slabs owing to the fact that for each unit area at the ends of the slabs, there will be approximately several times the amount of cooling surface than for each unit area at the sides of the slabs.

Thus, for instance, in a slab 4" wide, the end inch which is four square inches in transverse section would have 6" of the perimeter cooled, while a center inch which is four square inches in transverse section would have only 2" of its perimeter cooled.

In any event, in narrow slabs of this type the crystallization of the outer surface toward the center is so rapid that cooling at the ends becomes unnecessary.

In Figure 10, I have shown an adaptation of the structure of Figure 9 in the formation of billets of various cross-sectional arrangements. Thus, the plates 200, 201 of the inner copper surface 202 and the outer wall 203 which may be of any suitable material as, for instance, steel.

The walls 202 and 203 define the cooling chambers 208. Water enters the cooling chambers 208 through the vertical slot 210, and the water inlet pipe 205 moves horizontally through the chambers 208 and exits through the vertical slots 212 in the outlet pipes 206. The plates 200 and 201 are tied together by bolts 220 on opposite sides of graphite blocks 217, 218, 219.

The mold walls 202 in the opposite plates 200, 201 are recessed as at 230, 231 to conform to the cross-section of the billets to be made. Similarly, the graphite blocks 217, 218, and 219 are recessed as at 232 to conform to the cross-section of the billet to be made. The cooling operation is identical with that described in connection with Figure 9.

Thus, it will be seen that my novel principle of uniform cooling of the vertical mold by horizontal flow at high speed through the water jacket around the mold is applicable to the formation of billets by continuous casting operations, irrespective of the cross-sectional arrangement of the billets.

By the means herein described, therefore, a simplified highly efficient cooling system is provided particularly adapted to a continuous casting mold and so arranged that maximum heat exchange occurs by reason of the uniform hori-

zontal rapid flow of the large volume of water.

By this means uniform cooling of the entire mold is obtained over the entire perimeter and vertical height of the mold thereby permitting a uniform cooling operation of the entire contents of the interior of the mold.

In the foregoing, I have described my invention solely in connection with preferred illustrative embodiments thereof. Since many variations and modifications of my invention should now be obvious to those skilled in the art, I prefer to be bound not by the specific disclosures herein contained but only by the appended claim.

The term "continuous casting" refers to processes known in the art as semi-continuous casting as well as to continuous casting. The two processes are essentially the same. The semi-continuous casting operation is intermittent because no mechanical means is provided for cutting the billets to length. In the continuous casting operation, mechanical means are provided for cutting the billets to length.

In the following claim, therefore, the term "continuous casting" refers to a process where the length of the billet is greater than the length of the mold.

I claim:

A cooling system for a vertical mold, said cooling system comprising a jacket outside of and concentric with said mold defining a tubular chamber surrounding said mold; a source of cooling fluid under pressure; a hollow connecting member connecting said source of cooling fluid and said chamber; said hollow connecting member including a vertical inlet slot in said jacket extending substantially the full vertical height of said chamber, said tubular chamber guiding said cooling fluid through said chamber in a substantially horizontal path from said vertical inlet slot to said vertical outlet slot, said inlet slot being tapered from a relatively narrow opening at the top to a relatively wider opening at the bottom and vertical baffles carried by said jacket extending into said chamber for increasing the turbulence of said cooling fluid as it flows through said chamber; said baffles being relatively wider at their upper ends and relatively narrower at their lower ends.
